United States Patent Office.

JOHN MARTINO, JACOB BEESLEY, AND JOHN CURRIE, OF PHILADELPHIA, PENNSYLVANIA, ASSIGNORS TO CHARLES SHARPE AND EDGAR L. THOMSON.

Design No. 3,483, dated May 11, 1869.

DESIGN FOR A COOK'S STOVE.

The Schedule referred to in these Letters Patent and making part of the same.

To all whom it may concern:

Be it known that we, JOHN MARTINO, JACOB BEESLEY, and JOHN CURRIE, of the city and county of Philadelphia, and State of Pennsylvania, have originated a new Design for Complete Cook-Stove, of which the following is a full, clear, and exact description, reference being had to the accompanying drawings, making part of this specification.

Figure 1. A, upper front, with heavy round corners, forming panels, ornamented in the centre of each with shield and scroll, of Elizabethan style, the centre of the upper front proper with plain oval, with the name-standard, around which is a succession of scrolls, connecting with rosettes at the top and bottom.

Figure 2. B, oven-door, the moulding of which is ornamented with a beaded and pointed ornament. The

face of the door is of circular form, on which is a design of same style as fig. 1, A.

Figure 3. C, small end fire-door, of circular face, ornamented with scrolls and darts pointing up and down.

Figure 4. D, front fire-doors, of same design as fig. 3, C.

What we claim as our invention, and desire to secure by Letters Patent, is—

The design for a complete cook-stove, as herein set forth.

JOHN MARTINO. [L. S.]
JACOB BEESLEY. [L. S.]
JOHN CURRIE. [L. S.]
